UNITED STATES PATENT OFFICE

2,515,578

SELF-SUSTAINING FOG NOZZLE

Sam R. Wilson and George Kraulik, Vallejo, Calif.

Application January 20, 1947, Serial No. 723,068

2 Claims. (Cl. 299—109)

1

This invention appertains to new and useful improvements in fire fighting apparatus and has for its general object the provision of novel and improved means to assist and protect fire fighters.

Specific objects of this invention are as follows; to provide means for conducting a mist or fog from the fluid stream within a nozzle; to provide means for controlling the mist or fog extracted from the nozzle; to provide improved means for providing fresh breathing air; to provide an efficient, practical, improved device for protecting firemen in waging their fight against fires.

Other objects and features of novelty, as well as those mentioned hereinabove, will become apparent to those skilled in the art, in following the description of the preferred embodiment of the instant invention, illustrated in the accompanying drawings, wherein:

Figure 1 is a primarily elevational view, with parts in section, showing the preferred embodiment of the instant invention; and,

Figure 2 is an elevational view of the invention disclosed in Figure 1 and taken substantially in the direction of the arrow at 2.

Reference is now made in detail to the illustrated preferred embodiment of the present invention wherein a nozzle is provided and is generally indicated by the numeral 10. This nozzle of relatively conventional structure having the usual handle 12 adjacent the rear thereof and the direction ring 14 at substantially the center thereof. The usual lugs 16 and 18 are provided adjacent the end threaded portion 20 of the said nozzle 10.

Secured to the cylindrical portion 22 of the said nozzle 10, is a pair of radially disposed conduits 24 and 26 respectively. Any suitable securing means may be used to join these conduits to the longitudinal portion 22. Obviously, they may be screw threaded, brazed, welded, etc. The said conduits 24 and 26 have adjacent the free end thereof elbows or bends 28 thereby directing the dispersing members 30 and 32 forward or in the same general direction as the flow of liquid through the nozzle 10. The said dispersing means 30 and 32 comprise a simple pair of baffles merely to give direction to the mist or fog picked up by the conduits 24 and 26 from the flow of liquid through the nozzle. In order to effect the spray or mist suitable protuberances or rough edges may be projected into the flowing fluid stream thereby dashing a very small quantity of water up into the conduits 24

and 26. It is understood, that the last mentioned expedient is optional and may be used if so desired.

A pair of valves 34 and 36 are provided in the said conduits 24 and 26 respectively and are adapted to control the flow of mist or fog through the said conduits. Suitable conventional actuating arms 38 may be provided on the valve stem to operate the same.

10 A conduit 40 having a bent or curvilinear end portion 42 is received longitudinally of the axis of the said nozzle 10. The portion 42 is adapted to project through the nozzle and extend exterior thereof. An elbow portion 44 is provided 15 adjacent the end opposite said portion 42 and projects through a suitable aperture 46 in the said longitudinal portion 22 of the said nozzle 10. Suitably secured to the end of the said elbow 44 is a flexible conduit 48 provided of any 20 suitable conventional material. Many conventional securing means may be employed to connect said conduit 48 with the said elbow 44, however, the removable threaded connection 50 is preferable. Operatively connected to the end 25 opposite the said threaded connection is a suitable mask 52 adapted to be received over the face of a fireman. Suitable straps 54 and 56 may be employed to secure the mask over the fireman's face, however, this forms no part of 30 the instant invention and accordingly any suitable conventional securing means may be used.

As water is introduced into the nozzle as is conventional, a high rate of flow is encountered therein. Air is co-mingled with the water flowing through the said nozzle thereby assisting in the fog or mist extracting means discussed hereinabove. Further, due to the shape of the member 42 the fluid dynamic characteristics of the flowing water in the nozzle act on the exposure 40 of the member 42 thereby rendering breathing of the firemen easier and cleaner, the mask 52 protecting the operator or fireman from a great majority of the smoke.

There has been described the preferred embodiment of an invention which recites improvements in fire fighting apparatus. Since there has been described only a single preferred embodiment of the instant inventive concept limitation is sought in accordance with the scope of the appended claims and not to the exclusion of various other embodiments falling in the purview of this invention.

Having thus described our invention what is claimed as novel and improved is:

1. A fire fighting protection device comprising

a nozzle, means for conducting air in said nozzle, a mask secured to said conducting means, said conducting means including a conduit extending longitudinally within said nozzle, a bend at the one end thereof exterior of said nozzle adapted to be exposed to the fluid dynamic properties of the flowing water in said nozzle after it passes therethrough, an elbow at the other end of said conduit extending through said nozzle, and another conduit secured to the terminal portion of said elbow and having said mask secured thereto.

2. A fire fighting protection device comprising a nozzle, means for conducting air in said nozzle, a mask secured to said conducting means, said conducting means including a conduit extending longitudinally within said nozzle, a bend at the one end thereof adapted to be exposed to the fluid dynamic properties of the flowing water in said nozzle, an elbow at the other end of said conduit extending through said nozzle, and a flexible conduit secured to the terminal portion of said elbow and having said mask secured thereto.

SAM R. WILSON.
GEORGE KRAULIK.
